UNITED STATES PATENT OFFICE.

GEORGE A. MATTERN, OF BERKELEY, CALIFORNIA.

BATHING-SUIT.

1,281,625.

Specification of Letters Patent. Patented Oct. 15, 1918.

Application filed October 9, 1917. Serial No. 195,618.

To all whom it may concern:

Be it known that I, GEORGE A. MATTERN, a citizen of the United States, residing at Berkeley, in the county of Alameda and State of California, have invented certain new and useful Improvements in Bathing-Suits, of which the following is a specification.

My invention relates to bathing-suits of the one-piece type, covering the torso in full and only so much of the nether-limbs as is necessary to retain the garment in place.

With suits of this type, which frequently are worn for many hours, whether in the water or while the wearer is lolling on the sands, convention requires the use of a pair of over-trousers, especially when out of the water, but which may or may not be discarded when the wearer is actually bathing. These trousers are, however, usually very much abbreviated, and being quite loose do not afford that protection which both modesty and decency require.

To meet these conditions, as well as to provide that ready access which nature demands in view of the length of time the suit is usually worn, the garment is sometimes provided at the crotch with a flap which is drawn up in front a short distance and is buttoned across the lower abdominal region of the garment. This expedient while answering in part, is not wholly effective, for its position and size, and its lines of fastening are not such as to fully confine those parts which it is the purpose to cover and conceal.

The object of my invention is to meet all these conditions in full, and in a simple and effective manner; and to this end my invention consists in the novel bathing suit which I shall now fully describe by reference to the accompanying drawings, in which—

Figure 1 is a front plan view of my bathing suit, showing its front opening closed.

Fig. 2 is a view, broken, showing the front of the garment thrown open.

The suit comprises a body portion 1 which at its neck 2 and arm-holes 3 is of the customary closed one-shoulder-button

type, and is adapted to cover the whole torso. The lower end of the body portion 1 is continued to form the abbreviated leg portions 4, with the usual gusset 5 let into the crotch.

With the exception of the neck and arm holes, and the opening in its lower part, hereinafter described, the body portion is permanently closed throughout its circumference.

In the front, the garment is open on the line 6—6, beginning at a point in the median line about at the navel region, and thence extending down to the front apex of the gusset, and along one side of the latter to 65 the leg portion on that side, and along the inner side of said leg to its lower extremity. This opening is provided on one side with a suitable facing 7 carrying buttons 8, and on the other side with a suitable overlapping fly 9 having button holes 10.

Thus a part of the body portion and the whole length of the leg portion may be unbuttoned and thrown back when required, but when buttoned, the garment constitutes 75 a perfect covering and is as confining as a pair of trousers.

Though I have described the opening as being in the front of the garment, it is obvious that it may be in precisely a corresponding position in the back. The drawings may therefore indicate either a front or a back plan.

I claim:—

A bathing suit having a closed torso portion of the one-shoulder-button type and abbreviated leg portions, with a gusset in the crotch, said suit having an opening from a point in the torso portion above and adjacent the gusset, and down by one side of 80 the gusset and along the inside of one of the leg portions to its extremity; and means for detachably closing said opening.

In testimony whereof I have signed my name to this specification in the presence 95 of two subscribing witnesses.

GEORGE A. MATTERN.
